IMPLEMENT TIRE

Charles C. Sons, Jr., Peoria, Ill., assignor to Caterpillar Tractor Co., Peoria, Ill., a corporation of California

Filed Jan. 22, 1970, Ser. No. 21,038

Term of patent 14 years

Int. Cl. D12—14

U.S. Cl. D90—20

FIG. 1 is a perspective view illustrating my new design for an implement tire;

FIG. 2 is an elevational view of the implement tire showing the tire tread design in plan; and

FIG. 3 is a cross-section through the implement tire along line III—III of FIG. 2 further showing additional detail of the tire tread design.

It is to be understood that the tread design continues as shown throughout the circumference of the tire and that the sidewall opposite to that shown in FIG. 1 is a mirror image thereof.

I claim:

The ornamental design for an implement tire, substantially as shown and described.
